UNITED STATES PATENT OFFICE

ALBERT S. HOWELL, OF CHICAGO, ILLINOIS, ASSIGNOR TO THE BELL & HOWELL COMPANY, OF CHICAGO, ILLINOIS, A CORPORATION OF ILLINOIS

PERFORATED STRIP FEED MECHANISM

Application filed December 14, 1928. Serial No. 336,015.

My invention relates particularly to motion picture machines although not limited to this use alone.

One of the objects of my invention resides in the provision of means for conveniently and accurately determining the usual compensating loops of a perforated strip between an intermittent feed guide and constant feed means feeding the strip to and from the guide, all with a view toward ease, speed and accuracy in the lacing of the strip on the feed mechanisms.

Another object of the invention resides in the provision of an apertured strip feed guide which provides adequate edgewise friction on the strip therein without tending to buckle the strip transversely.

With these objects in view my invention consists in certain features of novelty in the construction, combination and arrangement of parts by which the said objects and certain other objects, hereinafter appearing, are effected, all as fully described with reference to the accompanying drawings and more particularly pointed out in the appended claims.

In the said drawings—

Figure 1 is a side elevation of a motion picture projecting machine embodying my invention;

Figure 2 is an enlarged partial side elevation of the same showing parts in different positions and having a part broken away and shown in section;

Figure 3 is a partial sectional view taken on the line 3—3 of Figure 6, hereinafter described;

Figure 4 is a partial section taken on the line 4—4 of Figure 3;

Figure 5 is a perspective view of a portion of a perforated motion picture film strip, showing the form it takes in the intermittent feed exposure aperture guide of my invention;

Figure 6 is an enlarged partial front view of the machine with parts removed, broken away and shown in section; and

Figure 7 is a partial plan view of the machine.

Like characters of reference indicate like parts in the several views.

Referring to the drawings, 1 designates the body of the machine which is inclusive of a forward frame 2 disposed in a vertical rearwardly and forwardly extending plane. Slidably mounted, as designated at 3, on one side of the frame 2 for rearward and forward movement is a lens mount member 4 which is inclusive of a forwardly disposed rearwardly and forwardly extending bored portion 5 in which a projection lens 6 is adjustably mounted. See Figures 1, 2, 3 and 6.

Disposed at the rear of the lens mount member 4 is an apertured intermittent feed film guide consisting of the following. See Figures 2, 3 and 4. A rear face guide member 7 is secured on the body of the machine, and a front face guide member 8 is secured on the rear end of the lens mount member 4 for facewise movement therewith into and out of film retaining relation with the face 70 guide member 7.

The intermediate portions of the face guide members 7 and 8 are apertured, as designated at 9, in alignment with the lens 6 for co-operation of a film in the guide with this lens 75 in the projection of pictures from the film, this intermediate portion of the guide being straight in order that the film at the aperture be maintained flat.

The portions of the guide adjoining the 80 straight apertured portion thereof are curved longitudinally of the guide and forwardly of the plane of the apertured portion of the guide, as designated at 11, in order that the portions of a film at these portions be curved 85 longitudinally thereof in order to strengthen the film at these points against edgewise pressure.

Figure 5 illustrates the form which a film 12 takes in the guide, the straight portion of 90 the film at the straight apertured portion of the guide being designated at 13 and the longitudinally curved portion of the film at the curved portions of the guide being designated at 14.

Disposed at the curved portions 11 of the guide are pairs of edge guide members 15 which have a tensioned engagement with opposite edges of the film in the guide, these members 15 being carried on the lens mount 95 100

member 4 for forward and rearward movement therewith together with the front face guide member 8 for the lacing and unlacing of the film in the guide. See Figures 2, 3 and 4.

5 It will be observed that, by reason of the fact that the film is longitudinally curved at the points where the edge guide members 15 engage the same, adequate edgewise pressure may be exerted on the film without the film tending to buckle transversely.

10 Sliding movement of the lens mount member 4 is controlled by a forwardly disposed manually operated lever 16 pivotally mounted on the frame 2, as designated at 17, and provided with a crank pin 18 slidably engaging a vertical slot 19 on the lens mount member, the arrangement being such that the pin is substantially on crank center, as shown in Figure 3, when the lens mount member is in its rearward or closed guide position to lock the same in this position.

15 A pair of revoluble transversely disposed horizontal shafts 21 are carried on the frame 2, and are disposed respectively above and below the lens mount member 4. Secured on respective of the shafts 21 and disposed above and below the lens mount member 4 is a pair 20 of constant feed film sprockets 22 disposed in film feeding alignment with the intermittent film feed guide.

25 These sprockets are driven together in the same direction for feeding a film to and from the feed guide by means of gearing 23, the upper shaft 21 being driven in timed relation with a mechanism, not shown, for intermittently feeding the film in the guide by means including a shaft 24 and gearing 25. See Figure 6.

30 40 Mounted on the frame 2 and disposed respectively above and below the lens mount member 4 is a pair of studs 26, which are disposed in parallelism with the sprockets 22 and forwardly adjacent the ends of the 45 intermittent feed guide. See Figures 1, 2, 3, and 7.

45 50 Pivottally mounted on respective of the studs 26 is a pair of film retaining devices, each of which is inclusive of a pair of spaced retaining arms 27 which project forwardly from their studs between the lens mount member 4 and the adjacent sprocket 22 and have their forward ends formed, as designated at 28, to retain a film engaged on the 55 adjacent sprocket.

55 60 These retaining devices are angularly movable into and out of retaining relation with the sprockets 22, and the forward portions of the arms 27 are slidably engaged in slot formations 29 on the lens mount member 4. Transverse studs 31 extend across the slot formations 29 and engage cam formations 32 formed on the arms 27 to move the arms 27 into film retaining position with rearward feed guide closing movement of the lens

65 mount member and to permit movement of the arms 27 out of film retaining position with forward feed guide opening movement of the lens mount member, spring means, hereinafter described, serving to move the arms 70 75 27 out of film retaining position.

Thus are the opening and closing of the feed guide and the movement of the retaining arms 27 into and out of film retaining relation with the sprockets 22 controlled together, 75 movement of the lever 16 into one position serving to close the feed guide and position the arms 27 in film retaining position, as shown in Figures 1 and 3, and movement of this lever to its opposite position serving to open the feed guide and to position the arms 27 out of film retaining position, as shown in Figure 2.

80 A pair of loop determining members 33 of U-shape are pivotally mounted by means of the legs thereof upon respective of the studs 26, the transversely disposed intermediate portions 34 thereof being curved in cross section for engagement with a film between the front face guide member 8 and respective 90 of the sprockets 22 for determining the compensating loops of the film between the sprockets and the intermittent feed guide.

95 These members are angularly movable into and out of loop determining position, studs 35 on the frame 2 limiting movement of these members in their loop determining position, as shown in Figure 2, and these members being movable forwardly out of this position and out of engagement with the film, as 100 shown in Figures 1 and 3.

105 Torsion springs 36 are engaged on the studs 26 and engage adjacent arms 27 with ends thereof to move the arms 27 out of film retaining position and engage adjacent legs of 105 the loop determining members 33 with their other ends to move the same into loop determining position against the stop studs 35.

110 The legs of the loop determining members 33 are provided with lugs 37 which are engaged by abutments 38 on the lens mount member 4 to move the members 33 out of loop determining position with rearward guide closing movement of the lens mount member. See Figures 1 and 3.

115 Thus, the lever 16 not only controls the opening and closing of the feed guide and the movement of the arms 27 into and out of film retaining position, but also controls the movement of the loop determining members 120 33 into and out of loop determining position.

125 Specifically, movement of the lever 16 into its upper position, as shown in Figure 4, positions both the arms 27 and the front face guide member 8 out of film retaining position, for the lacing of the film, and also positions the members 33 in loop determining position for determining the compensating loops in the lacing of the film. Movement of the lever 16 into its lower position, as 130

shown in Figures 1 and 3, positions both the arms 27 and the front face guide member 8 in a film retaining position for the operation of the machine, and also positions the members 33 out of loop determining position and disengaged from the film, for the operation of the machine to project pictures from the film.

Thus is provided simple and effective means for operating the arms 27 with the face guide member 8 and lens mount member 4, as well as for operating the members 33 with the arms 27, face guide member 8, and the lens mount member 4, the control thereof being by means of the single manually operated lever 16.

In the lacing of the film the mechanism is positioned as shown in Figure 2, before described, after which the film is trained about the front face guide member 8, with the guide members 15 edgewise engaging the film thereat, and about the members 33 and on the sprockets 22, as designated by the dot and dash line 39 in this figure, the teeth of the sprockets being engaged in perforations of the film so that the portion of the film between the sprockets and engaging the members 8 and 33 is taut.

Following this the lever 16 is moved to its lower position whereupon the arms 27 and the guide member 8 are moved to film retaining position and the members 33 are moved out of loop determining position with the film 5 engaged on the sprockets and in the feed guide and with loops 41, see Figure 1, of proper size between the feed guide and sprockets, the edge guide members 15 holding the film at the guide member 8 so that the loops of the film cannot change their length by the film shifting longitudinally at the guide member 8.

Unlacing of the film is effected by positioning the mechanism as shown in Figure 2 and removing the film.

Thus the compensating loops of the film are accurately determined without necessitating calculation, and it is to be further noted that the perforations of the film in the feed guide are positioned properly for engagement with the film engaging member of the intermittent feed mechanism, not shown, and that the film is properly positioned longitudinally with respect to the aperture 9 of the guide.

The film 5 is fed to and from the sprockets 22 from usual revoluble reels 42 carried on the machine, one of which is driven in a usual manner to take up or rewind the film fed thereto.

While I have described and shown the preferred embodiment of my invention I do not wish to be limited to the precise details of construction as changes may readily be made without departing from the spirit of my invention, but having thus described my in-

vention, I claim as new and desire to secure by Letters Patent the following:

1. In a perforated strip feed mechanism the combination with an intermittent feed guide, a constant feed sprocket associated therewith and a slidably mounted lens mount member carrying a strip face guide member of said guide for facewise movement into and out of strip retaining position, of a stud disposed in parallelism with said sprocket, a retaining member pivotally mounted on said stud for movement into and out of strip retaining position with respect to said sprocket, a loop determining member pivotally mounted on said stud for movement into and out of position to determine a compensating strip loop between said guide and sprocket and movable into its said position in the same angular direction as that with which said retaining member moves into retaining position, a stop limiting movement of said loop determining member in its said position, a torsional spring engaged on said stud and operating on said loop determining member with one end to move the same into its said position and operating on said retaining member with its other end to move the same out of its said position, means whereby movement of said lens mount member into face guide member retaining position effects movement of said loop determining member out of its said position, and means whereby this movement of said lens mount member effects movement of said retaining member into retaining position.

2. In a perforated strip feed mechanism the combination with an intermittent feed guide, a slidably mounted lens mount member carrying a strip face guide member of said guide for facewise movement into and out of strip retaining position, and a pair of constant feed sprocket means for feeding a strip to and from respective ends of said guide including retaining means movable into and out of retaining position, of a pair of loop determining members movable into and out of predetermined positions to determine compensating strip loops between said guide and said sprocket means, means whereby said retaining means is positioned in and out of its said position respectively with movements of said lens mount member into and out of face guide member retaining position, and means whereby said loop determining members are positioned in and out of their said position respectively with movement of said lens mount member out of and into face guide member retaining position.

3. In a perforated strip feed mechanism the combination with an intermittent feed guide, a slidably mounted lens mount member carrying a strip face guide member of said guide for facewise movement into and out of strip retaining position, a pair of constant feed sprockets for feeding a strip to and

from respective ends of said guide and disposed on opposite sides of said lens mount member, and a pair of retaining members movable into and out of retaining position with respect to said sprockets, of a pair of loop determining members movable into and out of predetermined positions to determine compensating strip loops between said guide and sprockets, means whereby said retaining members are positioned in and out of their retaining position respectively with movement of said lens mount member into and out of face guide member retaining position, and means whereby said loop determining members are positioned in and out of their said position respectively with movement of said lens mount member out of and into face guide member retaining position, said feed guide being inclusive of edge guide members carried with said lens mount member and frictionally engaging the strip to maintain said strip loops as determined by said determining members.

4. In a perforated strip feed mechanism the combination with a feed sprocket, an intermittent feed guide in feeding relation therewith and a slidably mounted lens mount member carrying a strip face guide member of said guide into and out of strip retaining position, of a retaining member pivotally mounted for movement into and out of retaining position with respect to said sprocket, and cam means for effecting movement of said retaining member into and out of retaining position respectively with movement of said lens mount member into and out of face guide member retaining position.

5. In a perforated strip feed mechanism the combination with an intermittent feed guide, a slidably mounted lens mount member carrying a strip face guide member of said guide for facewise movement into and out of strip retaining position, a pair of constant feed sprockets for feeding a strip to and from respective ends of said guide and disposed on opposite sides of said lens mount member, of a pair of retaining members pivotally mounted on opposite sides of said lens mount member corresponding with said sprockets for movement into and out of retaining position with respect to adjacent sprockets, springs yieldably urging each of said retaining members in one direction, and cam devices opposing said spring means for effecting movement of said retaining members into and out of their said position respectively with movement of said lens mount member into and out of face guide member retaining position.

6. In witness whereof I hereunto affix my signature this 11th day of December, 1928.

ALBERT S. HOWELL.
